UNITED STATES PATENT OFFICE.

CHARLES H. DANA, JR., OF WEST LEBANON, NEW HAMPSHIRE.

CALENDAR.

SPECIFICATION forming part of Letters Patent No. 283,215, dated August 14, 1883.

Application filed April 21, 1883. (No model.)

To all whom it may concern:

Be it known that I, CHARLES H. DANA, Jr., of West Lebanon, in the county of Grafton and State of New Hampshire, have invented 5 a new and useful Improvement in Calendars, of which the following is a full, clear, and exact description.

My invention consists in a monthly calendar composed of a rotating disk having a peculiar arrangement of figures, which is combined with a card or frame having an opening for exposing a portion of the disk, as herein-after described and claimed.

Reference is to be had to the accompanying drawings, forming a part of this specification, in which similar letters of reference indicate corresponding parts in both figures.

Figure 1 is a front elevation of my improved calendar. Fig. 2 is a face view of the disk detached.

The frame A is made of pasteboard or other suitable material, and is formed with a segmental opening, *a*, in a portion of its surface. B is a circular disk, attached to the back of the frame A by a rivet, *b*, so that a portion or segment of the disk is visible through the opening *a* of the frame. The numbers representing the days of the month are upon the outer portion of the disk B in radial columns. As shown, there are three sets of these numbers, each set occupying one-third of the disk, and each set of numbers, from 1 upward, is arranged in several columns and on spiral lines, so that above the number 7 of any one set there

is a space or break, opposite which the number 35 *1* of the next set comes, thereby avoiding confusion. One set consists of the numbers 1 to 30, inclusive, and the other two, 1 to 31, so that they are adapted for the months containing different numbers of days. 40

The names of the months are placed at the tops of the columns of figures in their proper places, so that each month will be exposed through a slot, *d*, formed in the frame A.

By this construction and arrangement, when 45 the disk is turned to show the name of any month at the opening *d*, the figures exposed at the opening *a* are correct for that month. I have shown but three sets of figures; but there may be four, the fourth one being for an arrangement of figures suitable for February, and in that case but one-fourth of the face of the disk will be exposed.

This calendar is very compact in construction and convenient for use, as both the name 55 of the day and the month appear at once.

Having thus described my invention, I claim as new and desire to secure by Letters Patent—

In a calendar, a disk having upon its face three sets of figures arranged in spiral lines 60 and radial columns, in combination with the frame having segmental sight-opening, as shown and described.

CHARLES H. DANA, JR.
